MASSAGING DEVICE OR LIKE IMPLEMENT

Victor Sommer and Bruno R. Roberts, Jamaica,
and Fritz M. Faust, St. Albans, N. Y.

Application March 29, 1939, Serial No. 264,722

13 Claims. (Cl. 128—24.1)

This invention relates to a combined massaging, heat and light ray treatment device or like implement.

It is an object of the present invention to provide a very efficient, economical and practical device capable of moistening the skin to be treated during the massaging operation, heat and light rays being simultaneously supplied by said device.

10 It is another object of the present invention to provide exchangeable means to readily and easily apply the desired moistener carrier to the skin; there may be provided a plurality of skin moistener carriers for selection for the particular treatment required.

Still another object of the present invention resides in the provision of heat conducting means from the lamp within the device to the working surface of the latter.

20 Another object of the present invention is to provide ducts in the housing of the device and also in the aforesaid conducting means to permit escape of heat from the lamp which otherwise would be transmitted or conducted to the handle 25 of the device; and to this end to construct the housing so as to minimize contact between it and the said conducting means.

Yet another object of the present invention is to provide in such a device ducts in the said 30 conducting means in such manner as to further function as an advertising medium by arranging the ducts in a predetermined form.

It is a further object of the present invention to provide means in the head of said device for 35 removably retaining the aforesaid moistener carrier.

Still another object of the present invention is to provide in said head capillary means for 40 retaining skin treating matter therein and facilitating its use during treatment of the skin.

It is still a further object of the invention to adapt a moistener carrier having a spongy construction which may form said capillary means.

The foregoing and other objects and features 45 of the invention will become more clearly apparent from the following description, which is descriptive of the preferred embodiments of the invention illustrated in the accompanying drawing. However, the embodiments herein shown and described being for purposes of illustrations only, it is to be understood that such modifications may be made, when desired, within the scope and spirit of the invention as claimed.

55 In the drawing:

Fig. 1 is a top view of a device made in accordance with the invention.

Fig. 2 is a side elevational view of the device partly in section;

Fig. 3 is a sectional view taken along line 3—3 of Fig. 2;

Fig. 4 shows a large fragment of the device partly in section and in a slightly modified form;

Fig. 5 is a top view of the housing of the device, shown in Fig. 4;

Figs. 6 and 7 are further fragmentary sectional views of the device in modified forms.

Referring now to the drawing, there is disclosed a housing 100 comprising a body 101 forming a handle and a preferably flared or enlarged head 15 or top piece 102. Within body 100 there is mounted on base 103 a lamp socket 104 carrying an electric bulb 105. Connected to socket 104 is a cable 106 carrying wires for connection with an electric power source (not shown).

20 Head 102 carries therewithin a metallic sleeve 107 which projects within the housing and adjacent bulb 105 and preferably surrounding the same when the head 102 is in adjusted position on body 101. Head 102 may be provided with a recess preferably of truncated formation within which is seated a moistener carrier 109. This carrier 109 is made of any suitable material but preferably of a spongy construction forming capillary means for holding and dispensing skin 30 treating matter, such as, for example, oil, cream, lotion, etc.

Lamp or bulb 105 may be either a heat or light source or both, the purpose of which is to facilitate the treatment of the skin during the application of the content of carrier 109 to the skin under treatment.

35 Head 102 provides a massaging surface workable by the movement imparted thereto by the operator's hand gripping handle 101 during the 40 application of the skin treating matter from the carrier. To facilitate treatment of the skin, heat from lamp 105 is transferred by radiation to metal sleeve 107, the latter conducting the heat to the head 102 and its stroking surface portion 45 110. This portion 110 is shown as being smooth and rounded. To minimize transference of heat from bulb 105 to the handle 101 metal sleeve 107 is perforated as indicated by numerals 111, 112 and the body 101 is fluted at 113 so as to provide 50 line-contact with the metal sleeve 107 as clearly shown in Fig. 3.

The perforations 111, 112 may be so arranged on sleeve 107 as to provide a preferred design, ornament or an indicia such as the word "Ellen" 55

(Fig. 4). The handle, although it may be made of any suitable material, such as from any of the well known moldable or plastic substances is in this case preferably made of translucent composition so that the light from bulb 105 through the said perforations will illuminate the handle portion adjacent said perforations to make the indicia visible to observer's eye.

Instead of providing a central recess 108 for 10 the head piece 102 for receiving therein the moistener carrier 109, there may be provided in head 110 one or more annular grooves or channels 114 which may be truncated in section and within which is placed the moistener carrier (not shown) 15 in the form of annuli (Fig. 7).

Fig. 6 discloses capillary bores 115 in inwardly projecting fingers 116 for containing any desired skin food, or skin treating material, such as massaging cream, oil, or medicament (not shown) 20 to be applied to the skin during the massaging operation. In Fig. 4 the moistener carrier 109 is held in a sleeve 117 in engagement with the inner circumferential wall 118 of recess 119. This engagement may be made frictional or screw 25 threaded.

Hollow body 101 and head piece 102 may be made either of similar or dissimilar materials and both or either may be translucent or transparent. Head piece 102 may be made of a material which will transmit only desired rays coming from ray emitting device 105, such as colored glass or suitable plastic composition.

Head piece 102 preferably has an arcuate recess 120 at its top surface. This recess provides on 35 account of its slanting wall a means for returning excessive skin treating material or the like to the carrier 109 which might have been pressed thereout during application thereof. It may be desirable that carrier 109 containing massaging oil 40 and the like projects beyond the top surface of head piece 102 or, as indicated in Fig. 6, very fine bores or recesses, such as capillary bore 115, which may hold skin treating matter, may be made flush with the top surface of head 102'. In the latter 45 case suction and evaporating effect facilitates the application of the skin treating matter, such as oil, to the skin to be treated. The said skin treating matter, for instance, a liquid, is placed in such bores 115 as by means of an eye-dropper.

50 During the operation of the device it might be desired and useful to apply different kinds of skin creams or skin treating medicaments to the skin to be treated. In such cases, a plurality of skin food carriers may be provided for replacement within head piece of the device and these carriers may be inserted in the head piece recess with a suitable tool, such as a pair of pincers; or the carrier may be held in a ferrule or sleeve which may be grasped by fingers of the hand and 55 then inserted in the recess (Fig. 4).

Head piece 102" (Fig. 7) where the channel 114 is provided adjacent the periphery of the head piece 102' may have a central heat transmitting portion 121, whereas head piece 102 (Fig. 2) may 60 have its portions 122, 110 surrounding the carrier 109 transparent and heat transmitting.

As clearly disclosed in Fig. 4 the heat conducting means or sleeve 107' is provided with an enlarged contact surface at its upper end forming 70 a channel-shaped member 123 which conducts a greater amount of heat to the thickened stroking portion 110' of the head piece 102'.

From the foregoing description taken in connection with the accompanying drawing it is apparent that improved simple, practical and inex-

pensive devices for the purpose intended are provided. It is apparent, however, that immaterial changes and modifications may be made by skilled persons without departing from the true spirit and scope of the invention as outlined in 5 the appended claims.

Having thus described the invention, what is claimed as new and desired to secure by Letters Patent, is:

1. An implement of the character described 10 comprising a hollow body forming a handle, a head piece, a working surface provided on said head piece, a heat and light rays emitting device located within said body for transmitting said rays through said head piece to said surface, heat 15 conducting means associated with said head piece and engageable with said body, said conducting means substantially surrounding said device to transfer heat therefrom to a predetermined portion of said head piece, and means adapted to 20 carry skin treating matter seated within said surface.

2. An implement of the character described comprising a body forming a handle, an electric heat and light source located within said body, a 25 massaging head having a top surface, a metallic sleeve fixed to said head and slidably engaging said body, said sleeve surrounding said source for transmitting heat from said source to said head, and moistener carrier means removably seated in 30 said top surface of said head and projecting therefrom.

3. An implement of the character described comprising a body forming a handle, an electric heat and light source located within said body, a 35 massaging head having a top surface provided with a slanting portion, a metallic sleeve fixed to said head and slidably engageable with said body, said sleeve substantially surrounding said source for transmitting heat from said source to said 40 head, and means for carrying skin treating matter centrally and removably seated in said top surface of said head, whereby said source transfers heat and light rays to said surface and simultaneously to said matter, whereas excessive skin 45 treating matter is returned to said means after application thereof to the skin, along said slanting portion of said surface.

4. An implement of the character described comprising a body forming a handle, an electric 50 heat and light source located within said body, a head having a massaging surface, a metallic member positioned between said head and said body, said member substantially surrounding said source for transferring heat therefrom to said surface, 55 and carrier means for containing skin treating matter therein removably seated in said surface and projecting therefrom, whereby said source transfers heat and light rays to said surface and simultaneously to said matter within said carrier 60 means.

5. An implement of the character described comprising a body forming a handle, an electric heat and light source located within said body, a 65 massaging head having a slanting top surface, a central recess in said surface, a metallic sleeve fixed to said head and slidably engaging said body, said sleeve surrounding said source for transferring heat from said source to said head, and spongy rubber means centrally and removably seated in said recess and projecting therefrom.

6. An implement of the character described comprising a hollow body forming a handle and provided with flutes at its inner wall, a head piece, 75

a working surface provided on said head piece, a heat and light rays emitting device located within said body for transmitting said rays to said surface, heat conducting means associated with said head piece and slidably engaging in line contact said inner wall, said conducting means being provided with apertures and surrounding said device, and capillary means for containing skin treating matter therein seated within a portion of said 10 surface.

7. An implement of the character described comprising a body forming a handle, an electric heat and light source located within said body, a massaging head having a top surface including 15 a stroking portion, a central recess in said surface, a metallic sleeve fixed within said head and provided with a free end, said end slidably engaging said body, said sleeve surrounding said source for transferring heat from said source to 20 said head, and spongy material centrally and removably placed in said recess and projecting therefrom.

8. An implement of the character described comprising a hollow body forming a handle and 25 provided with a grooved inner wall, a head piece, a top surface including a stroking portion provided at said head piece, a heat and light rays emitting device located within said body for transmitting said rays to said surface, heat conducting means fixed within said head piece and adjacent said portion, the free end of said conducting means slidably engaging in line contact said inner wall and being provided with apertures adjacent 30 said device, and capillary means for containing skin treating matter therein seated within a portion of said surface.

9. An article of the character described comprising a housing shaped to form a handle, said housing being open at its top, a head covering 40 said opening, a ray emitting device within said housing, a metal sleeve fixed to said head and extending within said housing and surrounding said ray emitting device, said head having a massaging surface, said sleeve having a horizontally disposed flange terminating in a vertically disposed flange whereby to provide a space between 45 said vertical flange and the body of said sleeve, said sleeve being secured to said head at said flange portions.

50 10. An implement of the character described

comprising a housing, a device for emitting heat and light rays located in said housing, a head piece connected to said housing, said head piece being provided with a light rays transmitting portion, a heat conducting portion and a stroking portion, a massaging portion, and moisture carrying means adjacent the surface of said head piece whereby the skin to be treated may be subjected to a moistening, massaging heat and light ray treatment. 10

11. An implement of the character described comprising a housing, a heat and light source located within said housing, a translucent massaging head piece in front of said source and connected to said housing, said head piece being provided on its surface with at least one recess for carrying skin treating matter, and heat conducting means positioned between said source and said head piece to transfer heat from said source to a predetermined portion of said head piece. 15 20

12. An implement of the character described comprising a housing, a device for emitting heat and light rays located in said housing, a head piece engageable with said housing and in front of said device, said head piece being made of 25 translucent material and being provided with a surface, means adapted to carry skin treating material received in a portion of said surface, and means adapted to conduct heat rays from said device to another portion of said surface, whereby 30 the skin to be treated may be selectively subjected to a moistening, heat, light and massaging treatment.

13. An implement of the character described comprising a housing, an electric lamp for emitting heat and light rays located within said housing, a head piece of translucent material in front of said lamp and closing said housing, heat conducting means placed between said lamp and said head piece and in close contact with the latter at a location to which heat is to be transferred by said lamp, and means for carrying skin treating material seated within the surface of said head piece, whereby said rays are directed toward said 45 carrying means and said surface of said head piece. 35 40
